COMBINED FOLDING TABLET PACK AND INTEGRAL CONTAINER

Edward Walter Tugwood, Iver Heath, England, assignor to Aspro-Nicholas Limited, London, England, a corporation of Great Britain

Filed May 20, 1965, Ser. No. 85,403

Claims priority, application Great Britain Nov. 26, 1964

Term of patent 14 years

(Cl. D58—2)

FIG. 1 is a perspective view of a combined folding tablet pack and integral container, showing my new design in a partially open position;

FIG. 2 is a similar view showing the sides not shown in FIG. 1;

FIG. 3 is a top plan view in closed position; and

FIG. 4 is an edge view in closed position.

I claim:

The ornamental design for a combined folding tablet pack and integral container, as shown.
